UNITED STATES PATENT OFFICE.

LIVINGSTON BOND KEPLINGER AND MARTHA QUIGGLE KEPLINGER, OF CINCINNATI, OHIO, ASSIGNEES TO THE PETERS CARTRIDGE COMPANY, OF CINCINNATI, OHIO, A CORPORATION OF OHIO.

OIL CUP.

Application filed September 24, 1921. Serial No. 503,907.

Our invention relates to oil cups and has for one of its objects the provision of a simple and efficient improved oil cup adapted to keep the oil clean and feed the latter to a bearing as such oil is used.

A further object of the invention is the provision of an improved oil cup having a wick therein to regulate the flow of oil from the cup.

10 A further object is the provision of simple and efficient improved means for automatically maintaining the oil cup closed, except when being filled.

15 Other objects of the invention will appear hereinafter, the novel features and combinations being set forth in the appended claims.

An embodiment of our invention is illustrated in the accompanying drawings forming a part of this specification and in 20 which—

Fig. 1 is a plan view of an oil cup including our improvement;

Fig. 2 is a central vertical section of the device shown in Fig. 1; and

25 Fig. 3 is a small elevational view of the oil cup shown in Fig. 1.

Referring more particularly to the drawings, we have illustrated an oil cup having a cup proper 21 which may be of any approved shape and size and be formed preferably of sheet metal. The bottom portion 7 of the cup is provided with a discharge passage 9 leading through the threaded portion 8 up into the oil reservoir 10. We provide a wick 11 in the passage 9 so as to retard the flow of oil from the cup and prevent dirt and foreign material from passing through the cup to the bearings to which the oil cup is adapted to be connected. Although 30 our improved oil cup is particularly adapted to be connected to bearings of a vehicle, it may have a general application. When connected to a vehicle, the jolting thereof will facilitate the passage of the lubricant from 35 the chamber 10 to the wick.

The bottom 7 of the oil cup may be of metal casting provided with a shoulder 19 which is engaged by a flange 20 of the sheet metal cover 21 which is provided with a 40 yielding opening 22 in its central portion in the top and in substantial alinement with the inverted cup 16. A spring 17 is located between an annular shoulder or seat on the tubular portion 23 and the lower peripheral

edge of the inverted cup 16. The spring 17 55 is preferably of such a strength as to hold the cup 16 tightly against the under side of the cover 21 so as to close the filling opening 22 against the entrance of dirt or other foreign materials.

When it is desired to fill the chamber 10 with oil, an oil can, not shown, or other instrument, may be inserted through the opening 22 and against the cup 16. Pressure is exerted by means of the nozzle of the oil 65 can sufficient to compress the spring 17 so that the oil can pass over the top of the cup 16 down into the reservoir 10. Upon removing the oil can or other instrument from the filling opening 22, the spring 17 will 70 again compress the cup 16 up against the cover 21 to close the opening 22.

A central tubular upstanding extension 23 from the circular bottom 7 is in communication with the discharge passage 9. 75 The wick 11 is extended up through the tube 23 with a portion of the wick disposed on the top of this tube. The inverted cup 16 is therefore slidably mounted on the outer side of the tube 23 and covers the portion 80 11' of the wick above the tube 23. The spring 17 presses up against the cup 16 so as to automatically close the opening 22.

Near the bottom of the tube 23 are a plurality of openings 24 which permit the oil 85 to pass from the reservoir 10 into the tube 23 and down into the passage 9 as well as upwardly by reason of the capillary attraction of the wick 11.

When the cup 16 is moved downwardly 90 to fill the chamber 10 with oil, the cup 16 presses the portion 11' of the wick, thereby tending to squeeze the oil down into the passage 9 and thence to the bearing to which the oil cup is connected. When the oil can 95 or other instrument is removed from the opening 22, the spring 17 moves the cup 16 up again, sealing the opening 22 and this tends to create a vacuum in the wick portion 11' so that when the cup 16 is released and 100 the spring 17 moves it back to its uppermost position, the wick again expands and tends to draw the oil up from the reservoir 10 into the wick portion 11' and into the wick filling the tubular portion of the exten- 105 sion 23.

It should be noted that the inverted cup 16 is entirely inside of the body portion of

the structure shown in the drawings. Normally the spring 17 presses the bottom of this inverted cup against the opening 22 so as to close the same, thereby keeping dust 5 and other foreign materials from entering the oil reservoir of the lubricator. The inverted cup 16 may be made of sheet metal and therefore readily stamped into the cup shape at low cost of production. When the 10 apparatus is assembled, the inverted cup 16 is held yieldingly in position to close the opening 22. The cup 16 therefore performs the double function of being the top of the inside oil reservoir 10 and of normally closing 15 the opening 22; the cup 16 also acts as a plunger cup to squeeze the oil down the passageway 9 and to suck the oil up along toward the upper end of the wick when the pressure on the inverted cup is released. Furthermore, the wick acts as a filter to prevent 20 any grit or foreign material in the oil from reaching the bearing to be lubricated.

We claim:—

1. An oil cup comprising a body having 25 a central discharge passage leading well up into the cup; a wick disposed in said discharge passage; and a spring-pressed cup member slidably mounted in said body and adapted to compress said wick when said 30 cup is moved against said spring action to force a lubricant out of said discharge passage.
2. An oil cup comprising a body having a discharge passage in its bottom portion 35 leading well up into the cup, there being a filling opening in substantial axial alignment with said discharge passage; a cup disposed against said filling opening; a wick in said discharge passage extending up into the 40 space thereabove and confined within said cup; and a spring pressing against the cup tending to move the latter up against said filling opening and relieving pressure on the portion of said wick in said cup.
3. An oil cup comprising a body having 45 a discharge passage in its bottom portion; a tube leading upwardly from said discharge passage; a wick in said tube and discharge passage with a portion of said wick disposed above said tube; an imperforated inverted cup disposed over and slidably mounted on said tube; the inner surfaces of the sides of said cup having a close fitting engagement with the outer surface of said tube; a spring pressing on said inverted cup tending to move the latter off of said tube.
4. An oil cup comprising a body having 55 a discharge passage in its bottom portion

and a filling opening in its top portion; a tube extending upwardly from said discharge passage and in open communication with the latter, there being an opening in the side of the tube at the bottom of the oil cup; a wick in said discharge passage and tube with a portion of said wick disposed above said tube; an inverted imperforated cup slidably mounted on said tube with its bottom closing said filling opening; and its sides having a tight fitting engagement with the sides of said tube; and a spring engaging 60 said inverted cup and tending to press the latter toward said filling opening.

5. An oil cup comprising a hollow body having a wick chamber and an opening adjacent the wick chamber; a wick in the wick 75 chamber; and an operable member engaging the wick and normally closing said opening, said operable member being adapted to confine the wick for movement away from the opening to compress the wick in a confined 80 space.

6. An oil cup comprising a body having an oil reservoir therein, said body having a filling opening in its top communicating with said reservoir, a tube extending from a passage in the bottom of said body into said reservoir with the upper end of said tube near said filling opening, said tube having a passageway from the lower portion of said reservoir to said passage in the bottom 90 of said body, a wick extending from said bottom passage into said tube and upwardly along the latter, a cap disposed over the upper end of said tube for confining said wick to the space therein and below the bottom of 95 said cap, and means to yieldingly hold said cap in position to close said filling opening.

7. An oil cup comprising a body portion having an oil reservoir therein, a passage in its bottom and a filling opening in its top, 100 a wick in said passage, means entirely inside of said body portion for closing said filling opening, a guide for said closing means, and mechanism for yieldingly holding said closing means against said filling opening 105 with a portion of said closing means exposed through said opening to permit pressure to be applied by extraneous means to open said filling opening to introduce oil into said reservoir.

In testimony whereof we have signed our names to this specification on this 8th day of September, A. D. 1921.
